WILLIAM M. CONNERY, OF PHILADELPHIA, PENNSYLVANIA

WALL COVERING AND SUPPORT THEREFOR

Application filed May 18, 1923. Serial No. 278,879.

In using superheated flues, super preheaters, hoppers, and various articles of this kind, in many instances it is essential and necessary to provide coverings constructed of various fibrous materials or a composition thereof, preferably asbestos with a composition material made therewith, for the retention of heat on the interior, so that the heat in passing through such structures may remain intensified, or at least at the approximate temperature as when the heat leaves its point of generation.

Many articles of this kind are provided with exterior reinforcements, and to apply such a covering, it is necessary to space the covering from the face of the structure to be covered, the purpose being to escape interference with any projections such as reinforcements on the exterior face of the structure.

In spacing such covering from the exterior surface of the structure to escape the reinforcement or other projections, a further purpose is accomplished, namely, that of providing an air space between the covering and the wall of the structure, thereby affording means to insure retaining the heat on the interior of the structure. In other words, the air space acts as an insulator.

Heretofore, the supports for supporting the covering and holding it spaced from the exterior surface of the wall of a flue or other structure have involved a rather expensive outlay, not only for the supports but also in time and labor; and then again, the supports are not as rigid as may be desired in many instances, particularly when the covering or flue, or other structure has been of long use.

To avoid such expense, time and labor, it has been found that supports may be made as integral parts of the heads of rivets or bolts, which are used as fastening, or riveting the various plates of the flue or the structure together. It has been found very practical to utilize this means for supporting the covering and holding it spaced, it being obvious that at the same time the plates are riveted or bolted, or otherwise fastened together. The supports are fastened to the sides of the structure, it remaining only nec-

essary to hang the covering on the supports.

Still another purpose is to provide, as an article of manufacture in the class of hardware, for the support of such covering.

Furthermore, it is the purpose to provide a combination wherein the supports act as the main element, in combination with a wall and in conjunction with a covering, such a combination resulting in the provision of an air space, and also affording means to hold the covering in position to escape the reinforcement or other projections on the wall structure.

It is to be understood that the particulars herein given are in no way limitative and that while still keeping within the scope of the invention, any desired modifications of the detail and desired proportions may be made in the apparatus according to the circumstances.

The invention comprises further features and combinations of parts, as will be herein-after set forth, shown in the drawings and claimed.

In the drawings:

Figure 1 is a view in perspective of a flue or wall structure showing the cover as applied thereto, portions of the covering being broken away in order to clearly illustrate the means for supporting the cover.

Fig. 2 is a vertical sectional view on line 2—2.

Fig. 3 is a transverse sectional view on line 3—3 of Fig. 1.

Fig. 4 is an enlarged detail sectional view of a portion of one of the supports, more clearly showing the means of fastening the covering to the support.

Fig. 5 is an enlarged detail perspective view of the support as an article of manufacture.

Referring to the drawings, 1 designates a wall of a flue or other structure, the wall being provided with reinforcements in the way of corrugations or stiffening ribs 2 made integral, which may be located in any manner, preferably at infrequent locations, such reinforcements being set forth, illustrated and claimed in Patents 1,416,334 and 1,416,335.

1,605,513 and as in similar patented structures.

To escape such projections or reinforcements, it has been found quite essential to construct supports 3 integral with rivets, bolts or similar fasteners 4, which are used for connecting the various plates of the flue or other wall together. These supports are in the way of projections which may be of any length and provided with any number of openings or perforations 5, which receive tie wires or tie rods 6, on which the cover 7 may be supported or suspended. This covering is mainly constructed of any suitable fibrous material, preferably asbestos, together with some other fibrous substance, for the purpose of retaining the heat on the interior of the flue or other compartment, there being an insulating air space 8 between the covering and the wall of the flue. The shank of the rivet or bolt, or other fastener, carries a nut, or the end of the shank is swaged or otherwise headed, as shown at 9.

These rivets or bolts or other fastenings are utilized for connecting the several metal plates in sequence for the purpose of making a flue or other article, while the support or cover carrying projection is an integral part of the bolt head.

This has been found a very essential means of providing a covering support, yet at the same time eliminating the necessity of welding or otherwise fastening the projections or supports subsequently to connecting the various metal plates together to construct the flue or other wall. It will be observed that the tie wires or cover supporting means carried by the projections may be passed through any one of the openings or perforations, or may be laced in and out of two or more of the perforations, as shown at 10, thereby providing additional reinforcing means for the covering.

Having set forth the invention, what is claimed is:

1. The combination with a flue or other wall comprising metal plates, of fastening means having heads for securing the several plates together, a covering, and means carried by the heads to support the covering.

2. The combination with a flue or other wall comprising a plurality of metal plates, with means to secure the several plates together, of a covering, and projections made as integral parts on the plate-fastening means, and including means such as may support the covering in spaced relation to the wall, hence causing an insulating or air space between the covering and the wall.

3. The combination with a flue or other wall comprising a plurality of metal plates, with means for securing the plates together, said means consisting of headed elements, of a covering for the wall, and projections operatively carried by the heads of said ele-

ments, said projections including means to support the covering in spaced relation to the wall, hence affording an insulating or air space.

4. The combination with a flue or other wall comprising a plurality of metal plates with headed members for securing the plates in place, of a covering for the wall, and projections constructed integrally with the heads of said elements and provided with openings to receive hanger means by which the covering may be held in spaced relation with the wall, accordingly affording an insulating or air space.

5. The combination with a flue or other wall comprising a plurality of metal plates with headed elements for securing the plates together, of a covering, and flat extensions made integral with the heads of said elements, said extensions having openings to receive hanger means consisting of tie wires entering said openings to support said covering.

6. The combination with a flue or other wall comprising a plurality of metal plates with headed elements for securing the plates together, of a covering, and flat extensions made integral with the heads of said elements, said extensions having openings to receive hanger means consisting of tie wires entering said openings to support said covering and accordingly causing an insulating or air space to be formed between the wall and the covering.

7. The combination with a flue or other wall comprising a plurality of metal plates with headed elements for securing the plates together, of a covering, and flat extensions made integral with the heads of said elements, said extensions having openings to receive hanger means consisting of tie wires entering said openings to support said covering, and accordingly holding the wall spaced sufficiently to escape projections on the wall and at the same time causing an insulating or air space to be afforded between the wall and the covering.

In witness whereof the inventor's signature is hereunto affixed.
